 Fritz, Dessau-Ziebigk, and Wilhelm Heck, Dessau, Germany, assignors to Junkers Flugzeug- und-Motorenwerke, Aktiengesellschaft, a corporation of Germany

Application April 15, 1939, Serial No. 268,102
 In Germany April 16, 1938

8 Claims. (Cl. 123—173)

This invention is directed to cylinder liners for internal combustion engines.

The mounting of cylinder liners in internal combustion engines provides difficulties in that the liners expand and distort under the heat from the combustion gases and the friction from the pistons. Joint separation thus occurs despite the use of joint packing and gaskets, and the efficiency of the engine is lowered by loss of compression.

It is an object of the invention to construct a cylinder liner for an internal combustion engine, which liner is movable without distortion from expansion due to the heat of the combustion gases within the cylinder.

Another object of the invention is to mount cylinder liners in an engine so that simple joint packings can be used and maintained.

Another object of the invention is to construct a cylinder which contains at least two cylinder liners of different sizes, and in which said liners are movable without distortion from expansion due to the combustion heat generated within the cylinders.

5 A further object of the invention is to make a tight connection between two different sized liners in an internal combustion engine, the connection not being distortable under the heat of combustion within the cylinders.

0 A further object of the invention is to maintain a tight packing between the connected ends of two different sized cylinder liners in an internal combustion engine.

Generally the objects of this invention are obtained by coaxially mounting two cylinder liners, which may be of different diameters, within the water jacket of an internal combustion engine, and separating the two liners by a member against which either one or both liners are resiliently pressed. The resilient pressing allows the liners to expand longitudinally under the heat developed in the combustion chambers, and remain sealed tightly against the connecting member.

5 These and other objects of the invention will be more fully understood by reference to the accompanying drawing, in which:

Fig. 1 is a cross sectional view of a water jacket enclosing liners according to one form of the invention;

Fig. 2 is a similar cross sectional view of a modified form of the invention; and

Fig. 3 is another similar cross sectional view of another modified form of the invention.

5 In Fig. 1, a water jacket 2 encloses liners 4 and 6 in the cylinder of an internal combustion engine. One end wall 7 of jacket 2 is bored at 8 to form an opening coincident with the opening through liner 4. The inner surface of wall 7 surrounding opening 8 is rabbeted at 10 for the re-

ception of packing material 12, against which the end 14 of liner 4 bears. Opposite bore 8, a coaxial bore 16 is formed in jacket end wall 17 through which one end of liner 6 projects. End wall 17 is detachably secured to the jacket by any conventional means, as by the bolts shown. Between liners 4 and 6, said liners being of different diameter as shown, a connecting member 18 is inserted, liners 4 and 6 bearing against opposite faces of member 18, the joints being sealed by 10 any heat-resisting packing material as shown at 20 and 22. Member 18 is in freely slidable engagement with embossment 24 formed on the inner surface of jacket 2. Liner 6 is provided with projections 26 which are slidably mounted against embossment 28 on the inner surface of jacket 2. The joint between projection 26 and embossment 28 may be sealed at 30 against the passage of liquid from the cooling space between cylinder liners 4 and 6 and jacket 2. Spring members 32 extend between the inner surface of end wall 17 adjacent bore 16 and the projections 26 to urge the liner 6 toward opposite end wall 7 of jacket 2.

The device is assembled and operates as follows:

25 Liner 4 is inserted into jacket 2 and seated on packing 12 on rabbeted edge 10. Connecting member 18 is then inserted into the jacket and is packed at 20 with respect to liner 4. Liner 6 is then inserted into the jacket. Liners 4 and 6, together with member 18, are longitudinally movable within jacket 2. Springs 32 are inserted together with liner 6, which springs bear against flange 26 and force liner 6 into engagement with connecting member 18 and liner 4, and keep both 30 liners and the connecting member in firm and positive engagement with one another. The liner 4 is shown of less length than the liner 6 and, because of its less length, has a thicker wall than liner 6. The liner is thus able to withstand the 35 pressure of the springs 32 urging the liner 6 and connecting member 18 against liner 4.

Heat developed in the cylinder from the combustion gases and the friction of the pistons causes the liners to expand. This expansion 45 takes place primarily longitudinally of the liners, and if the liners were rigidly joined to the jacket and to each other, they would distort and buckle, and the seal given by the packings would be destroyed. The construction of the instant invention allows the liners and the intermediate member to move longitudinally of the jacket, and therefore expansion of the liners can take place toward and against the springs 32, it being noted that liner 6 projects through the end wall of the 50 jacket so that there is no restriction to the movement of the assembled pieces 4, 18 and 6.

The arrangement is of very simple construction and allows an effective seal to be maintained between liners 4 and 6, the distortion of 55

the joint between these two different sized liners under the action of heat and friction developed within the combustion chamber being avoided. The springs 32 are merely illustrative of one form of resilient means for urging liner 6 toward liner 4. Obviously equivalent resilient means can be employed.

Fig. 2 shows a construction in which the liner having the small diameter may also have a lesser wall thickness than the liner with the larger diameter, and yet be resiliently pressed without harm against an intermediate connecting member. In this figure the water jacket is shown at 42, in which liner 44, of small diameter and little wall thickness, is axially aligned with liner 46, of larger diameter and greater wall thickness. The two liners are interconnected by intermediate member 48 which is freely and longitudinally slidable within jacket 42 and which normally bears against an annular flange 50 projecting inwardly from the inner wall of jacket 42. Liner 44 is provided with an annular flange 52 which slidably bears against embossment 54 on the inner surface of jacket 42. Springs 56 extend between the end wall of the jacket 42 and the flange 52 for urging the flange and the liner 44 against connecting member 48. In a similar manner liner 46 is provided with annular flange 58 which slidably bears against embossment 60 on the inner surface of jacket 42, said flange and liner being resiliently urged toward intermediate member 48 by springs 62. Springs 62 are made stronger than springs 56 so that intermediate member 48 is normally tightly engaged against flange 50. In this construction, the connection between the ends of liners 44 and 46 and the intermediate member is made in the nature of a ball and socket joint, the cylindrical surfaces having center points C and C', respectively, which lie on the longitudinal axis of the liners 44 and 46, and respectively directed towards the ends of the liners away from the connecting member 48. This allows displacement of the liners transversely of the longitudinal axis thereof without breaking the joint between the liners and the intermediate member 48. Longitudinal movement of the member, of course, is provided for through the resilient action of the springs 56 and 62, respectively.

Fig. 3 shows a construction which is similar to Fig. 2, except that instead of using the movable intermediate member 48, a fixed intermediate member 72 is used. Member 72 constitutes a diaphragm integral with jacket 42, said diaphragm being bored at its center to make an opening continuous with the liner 44. On the surface of diaphragm 72 and surrounding the boring centrally thereof is an annular wall 74 which provides a means for holding the liner 44 and the packing 76 in place. On the opposite face of diaphragm 72 a similar wall 78 holds liner 46 and packing 80 in place. Thus the resilient pressure applied to liners 44 and 46 is independent of the pressure applied to the other liner. The fundamental requirement lies in the selection of a suitable packing for 76 and 80. These liners must be exactly aligned in the beginning so that no displacement transversely of the longitudinal axis can take place through distortions under the heat of the combustion

chamber. In this respect, the walls 74 and 78 ensure that the longitudinal alignment of the liner is maintained.

The invention provides a very simple construction in which the liners of an internal combustion engine employing pistons of different size can be kept sealed with respect to each other and with respect to the fluid contained in the cooling chamber.

Having now described the means by which the objects of the invention are obtained:

We claim:

1. In an internal combustion engine having a cooling jacket, two cylinder liners of different size coaxially aligned and mounted for longitudinal movement within said jacket, an intermediate member mounted for longitudinal movement within said jacket and interposed and providing communication between said liners, and resilient means for holding said liners into engagement with said member.
2. In an engine as in claim 1, said resilient means comprising springs extending between a wall of said jacket and one of said liners.
3. In an engine as in claim 1, a stop element secured to the inner wall of said jacket for limiting the movement of said member in one direction, said means comprising first springs between one of said liners and a wall of said jacket and second springs between another wall of said jacket and a second liner and of greater strength than said first springs for urging said second liner toward said stop element.
4. In an engine as in claim 1, spherical surface engaging means between said member and the ends of the respective liners, each spherical surface having a center point on the longitudinal axis of its respective cylinder in a direction away from said member.
5. In an internal combustion chamber having a cooling jacket including side walls and end walls, two liners coaxially and movably mounted within said jacket and projecting through opposite end walls thereof, a flange secured to each of said liners, an intermediate connecting member mounted for longitudinal movement within said jacket between said liners, and resilient members between end walls and flanges, respectively, for holding said liners against said connecting member.
6. In an engine as in claim 1, a flange secured to at least one of said liners, and said resilient means being mounted to engage said flange.
7. In an internal combustion engine, a cooling jacket, a partition member mounted for longitudinal movement within said jacket, two axially aligned cylinders abutting opposite sides, respectively, of said member, and resilient means bearing against at least one of said cylinders for holding said cylinders into contact with said member.
8. In an engine as in claim 7, said jacket having an end wall, one of said cylinders having an end thereof bearing against said end wall, and said resilient means bearing against the other of said cylinders and urging the same toward said end wall.
